[57] CLAIM

The ornamental design for cord winder, as shown and described.

DESCRIPTION

FIG. 1 is a left side, front and bottom perspective view of a cord winder showing my new design, a perspective view taken 180° to it, is a mirror image thereof;

FIG. 2 is a bottom plan view thereof and the top plan view being a mirror image;

FIG. 3 is a left side elevational view thereof, the side opposite being a mirror image.

FIG. 1

FIG. 2

FIG. 3
